DESIGN FOR AN ELECTRICAL PLUG

Lancaster P. Clark, Jr., Fairfield, Conn.

Application July 3, 1939, Serial No. 85,826

Term of patent 14 years

To all whom it may concern:

Be it known that I, Lancaster P. Clark, Jr., a citizen of the United States, residing at Fairfield, in the county of Fairfield and State of Connecticut, have invented a new, original, and ornamental Design for an Electrical Plug, of which the following is a specification, reference being had to the accompanying drawing, forming part thereof.

In the drawing—

Fig. 1 is a front elevation of an electrical plug showing my new design, the prongs being shown in dotted lines.

Fig. 2 is a rear elevation.

Fig. 3 is a top plan view.

Fig. 4 is a side elevation; and

Fig. 5 is a bottom plan view.

The characteristic features of my design are shown in solid black lines in the drawings.

I claim:

The ornamental design for an electrical plug, as shown and described.
